Primary Examiner — Vy N Koenig

(57) **CLAIM**

The ornamental design for a projector screen with stand, as shown and described.

DESCRIPTION

FIG. 1 is a perspective view of a first embodiment of a projector screen with stand showing my new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an enlarged view of portion 9 shown in FIG. 1; FIG. 10 is an enlarged view of portion 10 shown in FIG. 1; FIG. 11 is an enlarged view of portion 11 shown in FIG. 1; FIG. 12 is an enlarged view of portion 12 shown in FIG. 8; FIG. 13 is a perspective view of a second embodiment of the projector screen with stand showing my new design; FIG. 14 is another perspective view thereof; FIG. 15 is a front elevational view thereof; FIG. 16 is a rear elevational view thereof; FIG. 17 is a left side elevational view thereof; FIG. 18 is a right side elevational view thereof; FIG. 19 is a top plan view thereof; FIG. 20 is a bottom plan view thereof; FIG. 21 is an enlarged view of portion 21 shown in FIG. 13; FIG. 22 is an enlarged view of portion 22 shown in FIG. 13; and, FIG. 23 is an enlarged view of portion 23 shown in FIG. 20. The dash-dash broken lines in the drawings depict portions of the projector screen with stand that form no part of the claimed design. The dot-dash broken lines represent boundaries of the enlarged portions and form no part of the claimed design.
